UNITED STATES PATENT OFFICE.

GEORGE KURSCHUS, OF HASTINGS, MICHIGAN.

DIES FOR FORMING HORSESHOES.

1,057,967.

Specification of Letters Patent.

Patented Apr. 1, 1913.

Application filed January 30, 1912. Serial No. 674,351.

To all whom it may concern:

Be it known that I, GEORGE KURSCHUS, a citizen of the United States of America, residing at Hastings, in the county of Barry 5 and State of Michigan, have invented certain new and useful Improvements in Dies for Forming Horseshoes; and I do hereby declare the following to be a full, clear, and exact description of the invention, such as 10 will enable others skilled in the art to which it appertains to make and use the same.

My invention relates to improvements in dies for forming horse shoes and more particularly to such dies for welding on toe 15 calks and finishing the shoe and its object is to provide automatic means for severing and welding the toe calks; for shaping the rear portions of the shoe and forming the nail creases or grooves and in various features of construction and arrangement as 20 hereinafter more fully described and particularly pointed out in the claims reference being had to the accompanying drawings, in which:—

25 Figure 1 is a plan view of the bed plate and lower dies; Fig. 2 a vertical section of the device on the line 2—2 of Fig. 1; Fig. 3 a vertical section on the line 3—3 of Fig. 1; Fig. 4 the same as Fig. 3 with the movable dies in lowered position; Fig. 5 a vertical section on the line 5—5 of Fig. 1 with the movable dies in raised position; Fig. 6 the same with the movable dies in lowered position; Fig. 7 a plan view of the horse 35 shoe blank ready to be operated upon by the machine; Fig. 8 a vertical section on the line 8—8 of Fig. 7; Fig. 9 a plan view of the finished shoe; Fig. 10 a vertical section of the same on the line 10—10 of Fig. 9; and 40 Fig. 11 the same on the line 11—11 of Fig. 9.

Like numbers refer to like parts in all of the figures.

1 represents a suitable bed plate to be attached to any suitable punch press.

45 2 an anvil plate inserted in the bed plate to support the blank where the toe calk is to be welded thereto.

50 3 are swaging dies having converging walls at each side of the heel portions of the shoe to swage the same horizontally when forced downward between the punches carried with the movable die.

4 is a cleat or holder attached to the anvil

plate to engage the concave side of the toe of the shoe and overlap the same to locate 55 and hold the shoe in proper position upon the anvil plate.

5 is a reciprocating slide movable on the bed plate 1 in ways 6. This slide has an opening 7 with an inclined wall at one end 60 engaged by a wedge 22 vertically movable in the opening to move the slide toward the shoe and in proper position to bring the cutting end 8 of said slide to act as one member of a shear to sever a portion from the 65 end of a bar of steel 9 to form the toe calk. This slide is provided with a longitudinal groove to receive the said bar 9 and properly guide the same to place with its end properly located over the toe of the shoe. 70

10 is a stop to properly locate the bar end-wise which stop is pivoted at 11 to swing out of the way when removing the shoe after it has been operated upon. This stop is normally held in operative position by a 75 spring 12 and a pin 13. The spring yields and permits the stop 10 to swing when the shoe is to be removed.

14 is a contractile spring to move the slide 5 back out of the way of the shoe and 15 an 80 adjustable screw which serves as a stop to limit the backward movement of the slide.

16 is a head to carry the upper die, the wedge and the punches provided with a suitable shank 17 to attach the same to the 85 plunger of a punch press (not shown). Attached to this head are two punches 18 adapted to enter between the dies 3 and force the shoe downward therebetween to swage the same and on these punches are 90 ribs or projections 19 which serve to form the nail creases in the shoe thus swaging the shoe laterally at the heel to make it thicker vertically and thinner horizontally as at 26^a and forming the nail creases 30 at the same 95 time. This head 16 also carries a die for severing and welding the toe calk having a recess 20 formed therein to shape the said toe calk and a shoulder 21 which moves downward past the toe of the shoe opposite the holder 4 and thus forms the front of the calk and also passes downward opposite the edge of the anvil plate 2 and thus forms a fin 29 on the front of the shoe while simultaneously welding and forming the toe calk 100 105 28. An opening 1^a through the bed plate

- receives the lower end of this die and also permits the escape of any surplus metal carried away by the same as it descends. The side angle of this die also co-acts with the cutting end 8 of the slide 5 to shear the bar 26 and sever the necessary metal from the same to form the toe calk. This head 16 also carries a spring pressed plunger 23 vertically movable therein and adapted to engage the bar 9 above the slide 5 and close to the cutting edge thereof. This plunger is held in the head by a longitudinally movable screw 25 surrounded by a spring 24 to yieldably engage the plunger with the said bar whereby the bar is held down and kept straight when it is sheared by the cutting end 8 of the slide and the side angle of the punch. This head also carries a wedge 22 having an inclined surface adapted to engage the end wall 7 of the opening 5^a in the slide 5 and as it descends moves the slide with its cutting end 8 properly located over the front of the shoe to sever the proper length of the bar 9 to form the toe calk.
- Push bars 27 are provided vertically movable in openings in the bed plate operated by any suitable mechanism (not shown) to raise the shoe out from between the side dies 3 after it has been operated upon.
- In forming the calk 28 and fin 29 there is considerable side strain on the punch and to take this strain a wear plate or block 1^b is inserted in the bed plate slidably engaged by the punch as it descends.
- From the foregoing description the operation of my device will be readily understood. The blank for the horse shoe as shown in Figs. 7 and 8 is heated to a welding heat at the toe and a forging heat throughout the remainder. The end of the steel bar 9 is also heated to a welding heat and placed in the slide with its end against the stop 10. The press is now operated and as the head 16 descends, the punch shears off the end of the bar 9 and welds it to the blank and also forms the fin 29 and calk 28. At the same time the punches 18 drive the heel portions of the shoe between the side dies 3 swaging the same and forming the nail grooves 30. As the head 16 rises again the slide 5 is retracted and the formed shoe lifted by the pushers 27 and manually removed from the machine.
- What I claim is:
1. Dies for forming horse shoes, comprising an anvil plate means for holding and adjusting a horse shoe blank, a reciprocating die, means coacting with the die to sever a portion from a rod, said die also adapted to engage and weld the severed portion of the rod to said blank.
  2. Dies for forming horse shoes, comprising an anvil plate, means for holding and adjusting a horse shoe blank, a reciprocating die having a calk forming recess and a

cutting angle, means co-acting with said angle to sever a portion from a rod, said die also adapted to engage the said portion to weld the same to said blank and form the same into a toe calk.

70

3. Dies for forming horse shoes, comprising an anvil plate, means for holding and adjusting a horse shoe blank, a reciprocating die adapted to sever a portion from a rod and weld the same to said blank, swaging dies having converging walls embracing the heel portion of the blank and punches adapted to force the blank between said walls.

75

4. Dies for forming horse shoes, comprising an anvil plate means for holding a horse shoe blank above said anvil plate, a die adapted to sever a portion from a rod and weld the same to the blank and also having a recess to form the same into a toe calk and a shoulder on the die adapted to form a fin on the shoe.

80

5. Dies for forming horse shoes, comprising an anvil plate, means for adjusting and holding a horse shoe blank, a reciprocable slide having a groove to receive a rod and a cutting end, means for reciprocating said slide, a die having an angle to co-act with said cutting end to sever said rod, and also adapted to weld the severed end to the blank and a movable stop to engage the end of the rod.

85

6. Dies for forming horse shoes, comprising an anvil plate, means for holding and adjusting a horse shoe blank, a slide having a groove to receive a rod and a cutting end to sever the same, a stop to adjust the rod, a reciprocating head carrying a wedge to engage and move the slide toward the blank, a spring to retract the slide, a die carried by the head coacting with the slide to sever the rod and adapted to weld the severed portion of the rod to the blank.

95

7. A die for forming horse shoes, comprising an anvil plate, means for holding a horse shoe blank with the toe of the same upon the plate, converging, swaging dies to embrace the heel portions of the shoe, a reciprocable head, a die carried by the head adapted to weld a toe calk to the blank and form the same, punches carried by the head adapted to force the said heel portions down between the swaging dies and ribs on the punches to form nail creases in the blank.

110

8. A die for forming horse shoes, comprising an anvil plate, a clip to hold a horse shoe blank in place on the plate, a slide movable toward and from the toe of the blank having a groove to receive a rod, a cutting end to sever the same and an opening to receive a wedge; a reciprocable head, a die carried by the head having an angle co-acting with the slide to sever a rod and a recess to form the severed portion of the rod and weld the same to the blank, a spring-

120

125

130

pressed plunger carried by the head and a wedge also carried by the head to enter the opening and move the slide.

9. A die for forming horse shoes, comprising a bed plate, a clip to hold a horse shoe in place on the plate, a reciprocable slide having a groove and a cutting end, a spring to retract the slide, a pivoted stop to engage the rod, a reciprocable head, a wedge carried by the head to move the slide, a die carried by the head to sever, weld and form a por-

tion of the rod, converging swaging dies to embrace the heel portions of the blank, punches carried by the head to force the blank between said dies and ribs on the 15 punches to form nail creases in the blank.

In testimony whereof I affix my signature in presence of two witnesses.

GEORGE KURSCHUS.
